UNITED STATES PATENT OFFICE.

ROY D. TOLMAN, OF WORCESTER, MASSACHUSETTS.

BALLOT-MARKING APPARATUS.

Application filed February 21, 1923. Serial No. 620,539.

To all whom it may concern:

Be it known that I, ROY D. TOLMAN, a citizen of the United States, residing at Worcester, in the county of Worcester, and 5 in the Commonwealth of Massachusetts, have invented a new and useful Improvement in Ballot-Marking Apparatus.

Since the Australian ballot system was 10 inaugurated a number of years ago, it has been the custom for the voter after receiving his ballot to go to a voting booth and mark the ballot. While a few voters have to ask for assistance in marking their ballot, the very large majority of the voters mark 15 their ballots independently. This independence has gone so far that many times the careless and poorly educated voter does not really know how to vote when he has been handed his ballot and in consequence 20 the crosses are made on any part of the ballot regardless of the instructions upon the ballot.

Thousands of ballots have been thrown 25 out as illegal every year for the reason that the crosses are not made in the proper legal spaces. Crosses are made under the name of the candidate, over the name and in many cases where it is impossible for the election 30 officials to determine the will of the voter. It is important that every vote or cross upon the ballot should count and to accomplish this object, I have invented a new apparatus for use in marking ballots which will make it impossible for a voter to mark 35 a ballot illegally.

Each State has a form of ballot and a 40 column in which the voter legally makes his crosses and I have so constructed my apparatus that a voter in any State with any form of ballot will have to mark his crosses in the proper spaces or columns if he votes at all. With my apparatus the voter cannot make a cross upon any part 45 of the ballot as he has been at liberty to do under the present old style methods of voting. I have arranged to cover over all of the ballot that should not be marked and in consequence, the voter cannot be misled in marking his ballot. The following 50 specification accompanied with drawings will clearly show the broad expanse to which my present invention may be adapted for all kinds of ballots at different elections.

55 Referring to the accompanying drawings,

Figure 1 is a plan view of my ballot marking apparatus.

Figure 2 is a front edge view of the same.

Figure 3 is a central sectional view upon line 3—3 Fig. 1.

Figure 4 is a similar section but showing the cover raised so that an open ballot may be placed within the apparatus.

Figure 5 is a plan view of a modified form of cover.

Figure 6 is a plan view of a modified form of apparatus adapted to be used with a different form of ballot.

The ballot marking apparatus as shown in the accompanying drawings comprises a base board 10 having securely mounted thereon a rectangular frame 11 which may be open on one side thereof as shown at 12 Fig. 2. The opening 12 is so provided that a ballot may be opened and slid into the apparatus for marking without having to raise the cover 13. While this method can be used in inserting a ballot, I prefer the method hereinafter described. The rectangular frame 11 forms a pocket 14 into which the unfolded ballot A is placed by the voter and it is a preferred form to raise the cover by the handle 31 when depositing a ballot for marking. While I have shown the cover 13 as hinged at 15 to the base board 10, the same may be securely fastened by means of a clip 16 and in this case the voter slides his ballot A through the opening 12 into the pocket 14 of the apparatus.

90 In the construction of the cover 13, I have shown a preferred form in Fig. 1 which is adaptable for use with the form of ballot as used in the elections of Massachusetts. The Massachusetts ballot has the columns for the crosses at the right of the candidate's name while with some other States, this column is at the left of the candidate's name. Therefore in describing this preferred form of cover with columns for crosses to the right of the name, I am aware that my apparatus can be made in either form without departing from the scope of my invention.

95 The cover 13 is recessed at 17 so that sheets of transparent material 18 such as celluloid or glass may be secured therein and the transparent material 18 may be held in place by means of pins 19. The sheets of transparent material 18 are so positioned 100 as to cover over all portions of the ballot which may be placed in the apparatus ex-

cept in the spaces wherein the crosses are to be made. In Fig. 1 I have shown the transparent material 18 with open spaces 20 at the right thereof large enough and no larger than the legal spaces upon the ballot, these spaces will allow a voter to mark his crosses only in the legal squares upon the ballot. With the Massachusetts form of ballot, the legal squares to the right of the names are the only legal spaces wherein the voter should mark his ballot and therefore with the body portion of the ballot covered, the voter can only vote in the legal spaces.

As a preferred method of placing an opened ballot in my apparatus, I believe it is best to raise the cover 13 with the transparent sections 18 held therein and furthermore it is desirable to limit the upward movement of the cover so that a voter in a voting booth cannot help but use the apparatus provided there for marking his ballot. If it was possible to raise the cover completely, a voter might mark his ballot without having to use the protective cover 13. To limit the upward movement of the cover 13, I fasten a stop-plate 21 upon the hinge side of the cover so that the cover can only be raised sufficiently to admit an opened ballot. In order to protect the edges of celluloid or glass and hold them in place, I bind them in ways 22.

While it has been shown that a ballot can be covered with glass or celluloid, it might be preferred to use this same material held in place as described but covered over with a printed form which would be a facsimile to the ballot printing in every detail. In this case the voter would not see his entire ballot except the spaces in which he was to make his crosses but he would see his entire ballot marked correctly when he removed it from the apparatus. Since a cover of this kind would have an appearance similar to that of the cover shown in Fig. 1 it is not shown in a separate drawing.

In Fig. 5 I have shown an apparatus having a covering of a slightly different structure, that of a wire mesh 23 instead of celluloid or glass. I believe that a wire mesh can be made so delicate and yet so as to obstruct a marking, that a voter could not mark his ballot except in the proper legal spaces.

While I have heretofore described a marking apparatus adapted for the Massachusetts form of ballot, I am aware that a number of other forms of ballots are now in use in other States which vary from the Massachusetts form. As an example of a different form of ballot, I have shown in Fig. 6 a ballot that has a party column and my invention can be applied to this form as well as to the Massachusetts form and at the same time, the voter can use it as readily.

In the apparatus as shown in Fig. 6 I

have made another modification in the manner of arranging the transparent sections 18. The construction of the cover 13 is very similar to that as shown in Fig. 1 except the transparent sections 18 are made up of individual units 24. Some of the units 24 especially those having the candidates' names beneath have slotted sections as shown at 25. It will be seen that with this form of ballot a variation no doubt would be made at every election in the listing of the candidates, so that different units would vary as to the make-up of the ballot. To allow for a change to be made, the individual units 24 are adapted to slide in place along the ways 22 similar to that shown in Figs. 3 and 4. After all units are properly arranged, the clamping bar 26 is secured to the cover 13 by means of screws 27. With this form of ballot in use, a circular opening 28 in the top section allows a voter to mark for his entire party by making a cross in this circular opening but should he decide to split his ticket and vote for a candidate in some office of the opposite party he would proceed further. The voter in splitting his ballot would mark a cross in the space opposite to the name of his choice in the other party column but while he voted a straight party ticket, the laws require that the name should be scratched through of that office in his party column. In order to allow a voter to scratch through a name if desired, I have provided slotted sections as at 25 to be placed over each candidate's name.

As an example of marking this form of ballot, I have shown a party column ballot in Fig. 6 so voted or split as to illustrate the principle of having slotted sections 25. In this case, the Republican candidate for alderman has been scratched as shown at 29 and a cross made in the opposite party column for that office. In constructing the cover, it is immaterial how the cover is hung for I have shown a different pivoted connection in each case. The entire marking apparatus may be secured to the shelf of a voting booth by means of screws passing through lugs 30 attached to the base board 10.

I claim:

1. A ballot marking apparatus comprising a base with a transparent cover for the ballot and a vertical column open in the cover.

2. A ballot marking apparatus having a transparent cover so constructed that the ballot is exposed for marking only in the legal sections.

3. A ballot marking apparatus having a transparent cover open in sections wherein the crosses are to be made.

4. An apparatus for marking ballots having a ballot pocket, a cover so constructed that the printing on the ballot is visible and

means whereby the ballot is exposed for marking only in the legal sections.

5. An apparatus for marking ballots having a window so constructed that the printing on the ballot is visible and an opening through the window in a specified column.

6. An apparatus for marking ballots having a ballot pocket, a cover adapted to be brought upon a ballot so that the printing 10 is visible and means whereby only specified sections of the ballot are exposed for marking.

7. An apparatus used in marking ballots having a base with a cover attached thereto, 15 a vertical column open in the cover and an opening in the base for the admittance of a ballot.

8. A ballot marking apparatus comprising a base forming a ballot pocket, a cover 20 so constructed that the printing on the ballot is visible and means for so covering the printing on a ballot that no marks can be made thereon except in the legal sections.

9. A ballot marking apparatus comprising a base for holding a ballot, a cover for covering over certain sections upon the ballot and means for preventing an inserted 25 ballot being marked without using the cover.

10. A ballot marking apparatus having a 30 ballot pocket with a cover thereto, a vertical column open in the cover and an opening through one side of the pocket adapted for the admittance of a ballot.

11. A ballot marking apparatus having a 35 ballot pocket, a cover so constructed of wire mesh that all printing on the ballot is visible and means whereby only specified sections are open for marking.

12. An apparatus for marking ballots 40 comprising a ballot pocket with a transparent cover open only in sections, said cover composed of individual units so united in ways that they form the body portion of said cover.

45 13. An apparatus for marking ballots comprising a ballot pocket having a cover constructed of individual units and means

for so mounting the units in ways that the arrangement of the units can be varied according to the makeup of the ballot.

50 14. An apparatus for marking ballots comprising a ballot pocket, a cover made up of individual sections adapted to be held in ways and a circular opening in the first section whereby a vote can be made therein for 55 the entire party ticket.

15. An apparatus for marking ballots having a base with a cover, said cover composed of plain and slotted sections held in ways and means for so altering the plain 60 and slotted sections that the slotted sections can be placed over the names of the candidates on the ballot.

16. An apparatus for marking ballots having a base with a cover made up of individual sections held in ways and slotted sections adapted to be placed over the names 65 of the candidates on the ballot.

17. An apparatus for marking ballots having a cover so constructed that all printing on the ballot is visible and openings 70 through the cover adjacent to each candidate's name.

18. An apparatus for marking ballots having a covering means which permits the 75 reading of the ballot therethrough and openings in the covering means whereby the ballot is exposed for marking only in the legal sections.

19. An apparatus for marking ballots 80 having a ballot pocket, means for admitting a ballot into the pocket and a cover adapted to hold a facsimile of the printing upon the ballot being used.

20. An apparatus for marking ballots 85 having a base with a cover attached, a vertical column open in the cover and means whereby the cover is adapted to support a facsimile of the printing upon the ballot being used.
